(No Model.)

R. H. EARLE.

APPARATUS FOR RAISING AND LOWERING BOATS.

No. 252,198.

Patented Jan. 10, 1882.

UNITED STATES PATENT OFFICE.

REGINALD H. EARLE, OF ST. JOHNS, NEWFOUNDLAND.

APPARATUS FOR RAISING AND LOWERING BOATS.

SPECIFICATION forming part of Letters Patent No. 252,198, dated January 10, 1882.

Application filed October 12, 1881. (No model.)

To all whom it may concern:

Be it known that I, REGINALD H. EARLE, of St. Johns, Newfoundland, have invented certain new and useful Improvements in Apparatus for Lowering and Raising Boats on Vessels, of which the following is a specification.

My improvements are designed to facilitate the lowering of boats from vessels under both ordinary and exceptional circumstances and to avoid the risk of the boats being swamped and overturned. Further, the object is to provide for this purpose an apparatus which shall not occupy unusual space nor prevent the use of the ordinary davits.

My improved apparatus consists of a swinging frame and gravity-cradle for carrying the boat bodily, and these are combined with davits in such manner that either can be used independently, all as hereinafter described and claimed.

Reference is to be had to the accompanying drawings, forming part of this specification, in which similar letters of reference indicate corresponding parts in all the figures.

In the drawings, Figure 1 is a perspective view, showing the apparatus in the lowered position. Fig. 2 is a side view looking from inboard of the apparatus in the raised position, and Fig. 3 is a side view showing the davits in use.

The apparatus is shown as applied at the forward part of the deck A; but in practice the position may be as most convenient.

35 B B are stands fixed on the deck at a suitable distance apart and constructed preferably in the double form shown—that is, of two stands or plates placed side by side, with space between for the davits.

40 C C are davits, attached by pivot pins or bolts a to the stands B, so that they may swing in and out a distance limited by their lower ends taking against cross-bolts of the stands.

45 b b are dogs pivoted on stands B, and provided with handles for their operation to clamp the davits in their inboard or upright position.

D is the swinging frame, consisting of arms c c, attached at their inner ends by knuckle-jointed connections d to the side of the vessel and braced by cross-bars e. The arms c are bent to carry their outer ends over upon the deck, and the frame is of a width to pass be-

tween the stands B when raised, as shown in Figs. 2 and 3.

E is the cradle, consisting of hooks f f, hung by joint-pins g to the outer ends of arms c, and connected at their outer ends by cross-bars h, that form a suitable support for the boat. On the inner ends of the hooks f there are double eyes k, to which blocks i are attached, and from these blocks ropes l pass to similar blocks, m, on the ends of davits C C. This tackle serves for raising and lowering the frame D with the cradle E.

On the stands B levers n are hung, and the levers are provided with projecting pins n', which, when the levers are raised, pass through apertures in the stands and in the arms c c for retaining the frame D in the raised position. On outer bar, e, of the swinging frame are 70 slides o o, provided with pins for engaging apertured lugs p on the hooks f, so as to retain the cradle in connection with the frame D and prevent the cradle from swinging out.

In the raised position of the apparatus the 75 boat rests in the cradle, which is entirely in-board, ready for use, and ropes q from eyes at the outside pass over the boat and are connected to hooks r on the lower ends of the levers n. The movement of raising levers n to 80 lock the frame tightens the ropes, while the reverse movement relieves the ropes.

The apparatus is operated as follows: To lower a loaded boat the levers n are moved out, thereby disengaging the frame D, the slides 85 o are moved inward to release the cradle E, and the frame then pulled out until it hangs by the ropes and the boat is clear of the vessel. The frame is then lowered by slackening the ropes, and as it swings outward the cradle also moves 90 out, and the boat is retained in the level position by gravity. The outward movement of the cradle is assisted and sudden oscillations prevented by the strain of the ropes attached to the upper ends of the cradle-hooks. As soon 95 as the boat floats it can be readily moved out of the cradle. When it is desired to use the swinging frame for towing boats it is to be lowered with the cradle E fastened back by the slides o, and the boats can then be attached 100 to the eyes k at the ends of arms c. To use the davits C in the ordinary manner, they are to be moved to their outward position, as shown in Fig. 3, which is permitted by pressing down

the handles of the dogs *b*, thereby releasing the dogs from the lower ends of the davits, so that their upper ends can move outward. The blocks *i* are to be removed from the hooks *k* on the frame *E* and connected with chains or eyebolts on the boat, and the boat thus swung from the davits in the ordinary manner, the cradle *E* remaining on deck to receive the boat.

This apparatus is without complicated parts liable to confuse or to get out of order. It occupies but little space on deck, and being combined with the ordinary davits, the objection that might arise to the use of the swinging frame in crowded streams and harbors is avoided.

The parts of the apparatus are to be made of any suitable material and constructed to combine lightness and strength.

Having thus fully described my invention, I claim as new and desire to secure by Letters Patent—

1. The combination of the swinging frame *D*, connected by cross-bars *e* and attached by knuckle-joints *d* to the side of boat, the cradle *E*, having hooks *f*, hung to the outer ends of arms *c* by joint-pins *g* and connected at the outer ends by the cross-bar *h*, and the davits *C C*, having blocks *m*, connected by ropes *l* and block *i* with eyes *k* on the hooks *f*, as and for the purpose specified. 25

2. The combination of the outwardly-movable levers *n*, having pins *n'* and hooks *r*, the inwardly-movable slides *o*, having pins, and the ropes *q*, with the apertured stands *B*, the frame *D*, having apertured arms *c e*, and the cradle *E*, having apertured lugs *p* on hooks *f*, as and for the purpose specified. 30 35

REGINALD HEBER EARLE.
